UNITED STATES PATENT OFFICE

RICHARD W. DINZL, OF BYWOOD, PENNSYLVANIA, ASSIGNOR TO SOUTHWARK FOUNDRY & MACHINE COMPANY, OF PHILADELPHIA, PENNSYLVANIA, A CORPORATION OF PENNSYLVANIA

HOSE PRESS

Application filed July 19, 1926. Serial No. 123,520.

One object of my invention is to provide a hose press of extreme length, which structure includes a horizontal base or bed, with matching die members or elements, preferably in the form of steam platens, each die element having a plurality of semi-circular recesses forming mold cavities in which lengths of hose may be cured; the lower die element or platen being fixed to the base while the upper die element or platen is vertically movable with respect to the same. By preference, these die elements or platens are of such dimensions as to provide a series of recesses in parallel arrangement widthwise of the same, so that a plurality of lengths of hose can be molded and cured at a single operation.

A further object of my invention is to provide upper and lower die members or elements of extreme length in the form of steam platens, which may be solid metal plates of the type set forth in my Patent No. 1,549,464, dated August 11, 1925, heated by the circulation of steam through continuous passages formed in said platens by drilling in the manner set forth in said patent.

A further object of my invention is to provide longitudinal stiffening members for the upper die element or platen in order that it may be maintained in a truly horizontal condition for proper engagement and perfect registry with the lower die element or platen.

A further object of my invention is to provide lifting means for the upper die element or platen, and to associate such lifting means with clamping means carried by said upper die element or platen for engagement with the lower die element or platen; such clamping means being thrown into and out of clamping position automatically, simultaneously with the operation of lowering and raising the upper die element or platen.

And a still further object of my invention is to provide means whereby the upper die element or platen may be lifted from a plurality of points simultaneously by the operation of a single fluid-operated piston contained within a cylinder mounted above the press.

These and other features of my invention

are more fully described hereinafter; reference being had to the accompanying drawings, in which:

Figure 1, is a side elevation on a greatly reduced scale, more or less diagrammatic, of a hose press within the scope of my invention.

Figs. 2 and 3, are enlarged views of a portion of the structure shown in Fig. 1; Fig. 2, being partly in section and Fig. 3, being in greater detail.

Figs. 4 and 5, are cross sectional views on the line III—III, Fig. 2; showing the upper platen or die member in the closed and open positions, respectively.

Fig. 6, is a diagrammatic plan view, showing the respective die members or platens partly in top view and partly in section, and

Fig. 7, is an enlarged sectional view illustrating a detail of my invention.

My improved hose press comprises upper and lower matching die members which, in the present instance, are in the form of steam platens, longitudinally grooved to provide mold cavities for the hose lengths when said die members are in closed and registering position; such platens being provided with continuous internal passages, preferably arranged in sections, for the circulation of a temperature controlling medium, usually steam, as set forth in my patent above referred to, and these passages may be arranged in groups or sections.

The lower die element, indicated at 1, may be supported by I-beams 2, embedded in a concrete base 3; such I-beams being spaced apart and positioned by means of bolts 4. The lower die element or platen is longitudinally grooved in parallel relation, as indicated at 5, to form the lower halves of a series of mold cavities for hose lengths, or articles of similar nature. The upper die element or platen, indicated at 10, is provided with similar recesses 5a, registering with those of the lower die element or platen, and such upper die element or platen is stiffened longitudinally by means of I-beams 11, which may be secured thereto by suitable bolts 12.

Pivots connected at each side of the upper die element or platen, throughout the

length of the same are clamping levers 15; the edges of such upper die member or platen being provided with brackets 16, secured thereto by belts 17, in which pivot pins 18, for said clamping levers are mounted. The lower ends of these levers are provided with inwardly projecting portions 19, which underlie the edges of the lower die element or platen when in the clamping position, and these projecting portions carry adjustable clamping blocks 20, secured thereto by bolts 21; said blocks being interposed between the projecting portions 19, and the edges of the lower die element or platen, when the press is in the closed position, as indicated in Fig. 4. Between these projecting portions 19, and the blocks 20, removable liners or shims 22, are placed, for a purpose hereinafter described.

The upper ends of these levers 15, are connected with brackets 25, carried by an I-beam 26, extending longitudinally of the press, by means of links 27, and such I-beam in turn is supported by cables 28, passing over sheaves 29, carried by a supporting frame 30; the opposite ends of said cables being connected to the end of a piston rod 31, whose piston 32, lies within a cylinder 33, also mounted on said supporting structure 30. This supporting structure may consist of a pair of I-beams 35, secured together in the form of a truss and suitably supported above the press, longitudinally of the same.

The several cables 28, are connected to the I-beam 26, by adjustable shackles 34, so that the respective cables can be properly adjusted to insure that any motion of the piston to elevate the I-beam 26, carrying the upper die element or platen will be synchronous; and in like manner, when it is desired to lower the upper die element or platen, a gradual exhaust of fluid-pressure from the cylinder 33, will permit the upper die element or platen to maintain its horizontal position while being lowered upon the lower die element or piston.

When the parts of the lifting mechanism are in the lowered position, indicated in Figs. 2, 3, and 4, the links 27 are spread apart by their bracket connections with the I-beam 26, so as to push the upper ends of the levers 15 outwardly, and bring the inwardly projecting portions with the clamping blocks 20, under the edges of the lower die element or platen I. The platens or die elements of the press are maintained in the closed position by the clamping levers 15; the spreading of the links 27 causing the lower ends to grip the same between the points of contact and the pivot pins 18.

As the upper die element or platen is lowered into place, the projecting portions of the levers 15 pass under the lower platen; further downward movement spreading the upper ends of the levers 15, and crowding the projecting portions 19, with the blocks

20, beneath the edges of the lower platen. To insure an even pressure upon the edges of the platens the blocks 20 may be adjusted to proper position by the insertion of liners or shims 22, between the same and the projecting portions 19. Upon imparting a lifting movement to the I-beam 27, when it is desired to raise the upper die element or platen, these clamping blocks are automatically released; the connection of said beam with the links causing the latter and the levers to assume the position shown in Fig. 5, with the lower engaging portions of such levers displaced outwardly, as clearly indicated in said view.

In order that the I-beam 26, with the upper die element or platen 10, and the several bracket connections and levers may be supported temporarily, while filling the mold cavities in the lower die element or platen or for other purposes, and to avoid an undue strain upon the lifting cylinder, the supporting frame 30 for the latter is provided with a series of depending hooks 38, and the I-beam 26 carries eye members 39, to be engaged by these hooks.

The continuous passages within the respective die elements or platens for the circulation of the temperature-controlling medium (usually steam), are provided with inlet and discharge openings, indicated at *a*, and *b*, respectively. By preference these passages are arranged or disposed as independent sections; the respective platens shown in the drawings having four such sections, indicated at *A*, *A'*, *A²* and *A³*.

In order that the platens may be positioned laterally to insure registry of the respective mold cavities, one platen, the upper one for instance, may have the edges of its meeting face recessed, as indicated at *c*, while the other platen will be provided with edge flanges *d*, fitting these recesses, as clearly shown in Fig. 4.

I claim:

1. The combination, in a hose press, of a lower die element disposed in fixed position; said lower die element comprising a metal platen having longitudinal recesses forming half molds for the hose, a complemental upper die element comprising a metal platen having longitudinal recesses registering with the recesses of the lower platen, longitudinal stiffening members for the upper platen, lifting means for said upper platen including a member extending longitudinally of and disposed above the same, levers pivotally mounted on the edges of said upper platen, and links connecting said longitudinal member to the levers pivotally connected to the upper platen; said levers having portions arranged to underlie the lower platen.

2. The combination, in a hose press, of a lower die element disposed in fixed position; said lower die element comprising a metal

platen having longitudinal recesses in parallel arrangement forming half molds for the hose, a complemental upper die element comprising a metal platen having longitudinal recesses registering with the recesses of the lower platen, longitudinal beams serving as stiffening members secured to the upper platen, lifting means for said upper platen including an I-beam extending longitudinally of and disposed above the same, a cylinder, a support therefor, sheaves carried by said support, cables connected to said I-beam and passing over said sheaves to the cylinder, levers pivotally mounted at the edges of said upper platen, links connecting said I-beam to the levers pivotally connected to the upper platen; said levers having portions arranged to underlie the lower platen, and adjustable clamping members carried by said underlying portions of the levers and adapted to be crowded against the under side of the lower platen.

3. The combination, in a hose press, of a lower die element disposed in fixed position; said lower die element comprising a metal platen having a series of longitudinal recesses in parallel arrangement forming half molds for the hose, a complemental upper die element comprising a metal platen having longitudinal recesses registering with the recesses of the lower platen, a pair of I-beams serving as longitudinally stiffening members for the upper platen, lifting means for said platen including an I-beam extending longitudinally of and disposed above the same, levers pivotally mounted on the edges of said upper platen, oppositely disposed links connecting the I-beam of said lifting means to the levers pivotally connected to the upper platen; each of said levers having an inwardly projecting portion arranged to underlie the lower platen and adjustable clamping members carried by the inwardly projecting portions of said levers and adapted to be crowded against the under side of the lower platen.

4. In a hose press, the combination of upper and lower die members comprising heating platens; each platen having a plurality of longitudinal recesses in registering position, vertically movable means for supporting the upper platen including an I-beam extending longitudinally of the press, brackets carried by the edges of said upper platen, levers pivotally mounted in said brackets and having portions underlying the edges of the lower platen, and link connections between said levers and the I-beam; said levers being adapted to swing on their pivotal connections to free their underlying portions from the lower platen upon imparting lifting movement to said I-beam.

5. In a hose press, the combination of upper and lower die members comprising heating platens; each die member having longi-

tudinal recesses semi-circular in cross section disposed in registering position throughout their length, means for raising and lowering the upper die member, brackets carried by the edges of said upper die member, levers pivotally mounted in said brackets and having portions adapted to extend under said lower die member, and links connected to the upper ends of said levers and having their inner ends connected to the means for raising and lowering the upper die member; said levers being moved into direct clamping relation upon lowering said links and swinging on their pivotal connections with said brackets away from the lower die member upon imparting lifting movement to said links.

6. In a hose press, the combination of upper and lower die members; each die member having longitudinal recesses disposed in registering position, vertically movable supporting means for the upper die member, brackets carried by the edges of said upper die member, levers pivotally mounted in said brackets and having portions adapted to extend under said lower die member, links connected to said levers, and means for raising and lowering said upper die member; said lifting means including a longitudinal member to which the inner ends of said link are pivotally connected, and said levers being moved into clamping position upon lowering said links and swinging on their pivotal connections with said brackets away from the lower die member upon imparting lifting movement to said links; the upper die member rising with such lifting movement and releasing said levers from their engagement with the lower die member.

7. The combination, with a hose press, having upper and lower die members, of clamping means comprising a series of brackets carried by the edges of the upper die members, independent levers pivotally mounted in each of said brackets; the lower ends of said levers having inwardly projecting portions adapted to underlie the edges of the lower die member, adjustable engaging means independently carried by said underlying portions of the levers, and means for imparting movement to said levers to move said inwardly projecting portions toward and away from direct engagement with the lower die member.

8. The combination, with a hose press, having upper and lower die members, of clamping means comprising a series of brackets carried by the edges of the upper die member, independent vertically disposed levers pivotally mounted in each of said brackets; the lower ends of said levers having inwardly projecting portions adapted to underlie the edges of the lower die member, detachable adjusting members independently carried by said underlying portions of the respective levers, links connecting the upper ends of said

levers and pivotally connected together intermediate their connections with the levers, and means for imparting vertical movement to said links whereby the lower ends of said levers may be moved toward and away from direct clamping engagement with the lower die member.

In witness whereof I have signed this specification.
